UNITED STATES PATENT OFFICE

CHARLES HEUZE, OF AUVELAIS, BELGIUM

GLASS-POLISHING APPARATUS

Application filed April 2, 1928, Serial No. 266,731, and in Great Britain May 24, 1927.

This invention relates to continuous glass polishing apparatus of the type in which the runners travel as well as the glass, and has for its object means whereby the different media required for polishing during different stages of the travel of each runner, are supplied to the runner.

In polishing glass by the above-mentioned type of apparatus, each runner has to be supplied with a medium which is different for different stages of travel of the runner. Customarily, rouge and water are employed as media, a mixture of rouge and water in varying proportions being supplied at some stages, while water alone, in varying quantity, is supplied at other stages. The invention is applicable to the supply of any media suitable for polishing, and the term "medium" or "media" is herein used to mean any substance or substances supplied to the polishing runners.

A receptacle is attached to each runner, which passes successively under the outlets of a plurality of fixed tanks and receives polishing medium therefrom during the travel of the runner and distributes the polishing medium to its felts.

In the accompanying drawings:—

Figure 1 is a side view of a portion of the polishing apparatus, largely diagrammatic;

Figure 2 is an end view of one of the polishing runners, partly broken away;

Figures 3 and 4 are views similar to Figure 1 showing alternative arrangements; and

Figure 5 is a sectional elevation of one constructional form of valve for the distribution of the polishing medium.

Referring to Figure 2, the glass 20 rests on the tables 21, which slide on fixed guides 22 and are caused to travel by the rack 23 and pinions 24.

The polishing runner shown in Figure 2 is of the type in which a frame 1 extends across the apparatus and carries a plurality of runner spindles 2, of which one only is shown. The runner frame 1 slides on fixed guides 25 and is caused to travel by chains 26 supported on rollers 27 and engaging projections 28 on the runner frame. The rotating runner spindle 2 is shown carrying two runner heads 3

with their felt pads 4. Since this runner spindle is of ordinary type, no further description is deemed to be necessary. Referring to Figure 1, the runner frames 1 are shown travelling in close proximity, the direction of travel being indicated by the arrow. A plurality of fixed tanks 5 contain the different polishing media adapted to the different stages of the polishing operation, and each has its outlet pipe 6 which may be controlled by a valve and is kept permanently open during the operation of the apparatus.

Attached to each runner frame 1 is a receptacle consisting of a double inclined trough 7, the left-hand end of the trough of one runner as viewed in Figure 1, overlapping the right-hand end of the trough of the following runner, so that the series of troughs 7 form a continuous trough system.

Referring to Figure 2, the outlet pipe 6 of one of the tanks 5 (which latter are not represented in the said figure) is shown immediately above the trough 7 here seen in end view, and attached to the runner frame 1 by a bracket 8. Immediately below the lowest point of the trough 7, which is there provided with an aperture, is a funnel 9 adapted to lead the medium supplied to the trough, into a distributing valve 10, attached to the runner frame by a bracket 11. From the distributing valve 10, a pipe runs towards each of the runner spindles on the runner frame. In the drawing three pipes are shown, one 12 running towards the runner spindle 2 shown, while the other two, 13 and 14, run towards similar spindles not shown. The distributing valve 10 is operated by a pulley 15, which is driven by a belt by any convenient means. The distributing valve 10 may be of any convenient type adapted to give passage to the medium contained in the body of the valve, to each of the pipes, 12, 13, 14 in turn.

A convenient form of valve is shown in Figure 5 in which a hollow spindle 29 rotated by the pulley wheel 15, leads polishing medium from the funnel 9 to the interior of the valve 10. The bottom of the valve has holes 30 adapted to lead the polishing medium to the pipes 12, 13, 14 (Figure 2). Attached to the spindle 29 is a plate 31 which

rests on the bottom of the valve and has a single hole 32. As the plate 31 turns, the polishing medium in the valve passes through the hole 32 to the holes 30 in turn.

6 Each pipe, as 12, delivers the medium into a circular trough 16 attached to, and rotating with, the respective runner spindle 2 and from this trough, pipes 17 deliver the medium to the glass.

10 A distributing valve, such as 10, is conveniently employed when there is a plurality of runner spindles on each runner frame, but when said frame has only a single runner spindle, it is unnecessary, and the pipe 12 can 15 pass directly from the aperture of the trough 7 to the trough 16. The distributing valve can also be dispensed with in the case of two or three runner spindles, the delivery pipes 12 etc., being all connected to a common funnel such as 9, but in this case accuracy in the 20 distribution is not so well ensured.

By referring to Figure 1, it will be seen that during part of the travel of each runner, its trough 7 is not receiving a supply 25 of medium. During this part of the travel, a continuation of the supply of medium to the glass may, if desired, be secured by suitable design of the aperture in the distributing valve 10 or of the trough or pipe outlets.

30 The supply of medium may, however, be made continuous from the tanks 5 to the glass, by suitably relating the length of each trough 7 to the distance between the tanks, as shown for example in Figure 3, where the runner frames 1 are shown spaced apart, and the 35 length of each trough is equal to the distance between adjacent tanks.

Alternatively, the trough 7 may be made 40 short but capable of containing sufficient medium to maintain an efficient supply during the travel of a runner from one tank to the next, as in Figure 4. In this case the outlet of each tank 5 is provided with a valve 18 which, as shown at the left-hand end of 45 Figure 4, is opened by a bar 19 attached to each of the troughs 7. When there is no trough under a tank, as is the condition represented at the right-hand end of Figure 4, the valve 18 of said tank is kept closed, by a 50 weight or spring (not shown).

The devices shown and described for the 55 automatic supply of polishing medium are convenient for the type of polishing runner illustrated, but these are to be regarded merely as convenient examples and are susceptible of various modifications for this or for different runners and apparatus without departing from the invention; for example, the pipes 6 instead of being directly connected 60 with the tanks as shown, may be supplied with media from the tanks under pressure.

Having described my invention, I declare that what I claim and desire to secure by Letters Patent is:—

65 1. In continuous glass polishing apparatus

in which both the glass and the polishing runners travel, the combination with a plurality of runner frames of a plurality of fixed tanks adapted to contain polishing media, a trough attached to each runner frame adapted to receive the media from the tanks during its travel and long enough to receive polishing medium for a considerable part of the time of travel of the runner frame from one tank to the next, and means conducting the media from each receptacle to the polishing pads of the runner frame.

2. In continuous glass polishing apparatus in which both the glass and the polishing runners travel, the combination with a plurality of runner frames, of a plurality of fixed tanks adapted to contain polishing media, a trough attached to each runner frame adapted to receive the media from the tanks during its travel and overlapping the trough of an adjacent runner frame so that a continuous trough is formed adapted to receive continuous supply from each tank, and means conducting the media from each receptacle to the polishing pads of the runner frame.

3. In continuous glass polishing apparatus in which both the glass and the polishing runners travel, the combination with a plurality of runner frames, of a plurality of fixed tanks adapted to contain polishing media, a receptacle attached to each runner frame adapted to receive media from the tanks during its travel, a valve controlling the supply from each tank, means connected with the runner frame adapted to open the valve of each tank during the passage of the receptacle under it and means conducting the media from each receptacle to the polishing pads of the runner frame.

4. In continuous glass polishing apparatus in which both the glass and the polishing runners travel, the combination with a plurality of runner frames and a plurality of runner spindles carried by each runner frame, of a plurality of fixed tanks adapted to contain polishing media, a trough attached to each runner frame adapted to receive the media from the tanks during its travel and long enough to receive polishing medium for a considerable part of the time of travel of the runner frame from one tank to the next, and a valve on each runner frame adapted to receive polishing medium from the receptacle thereon and to distribute the medium to each of the runner spindles on the frame in succession.

5. In continuous glass polishing apparatus in which both the glass and the polishing runners travel, the combination with a plurality of runner frames and a plurality of runner spindles carried by each runner frame, of a plurality of fixed tanks adapted to contain polishing media, a trough attached to each runner frame adapted to receive the media from the tanks during its travel and long enough to receive polishing medium for a considerable part of the time of travel of the runner frame from one tank to the next, and a valve on each runner frame adapted to receive polishing medium from the receptacle thereon and to distribute the medium to each of the runner spindles on the frame in succession.

- media from the tanks during its travel and overlapping the trough of an adjacent runner frame so that a continuous trough is formed adapted to receive continuous supply from each tank, and a valve on each runner frame adapted to receive polishing medium from the receptacle thereon and to distribute the medium to each of the runner spindles on the frame in succession.
- 10 6. In continuous glass polishing apparatus in which both the glass and the polishing runners travel, the combination with a plurality of runner frames and a plurality of runner spindles carried by each runner frame, of a plurality of fixed tanks adapted to contain polishing media, a trough attached to each runner frame adapted to receive the media from the tanks during its travel, a valve controlling the supply from each tank, 20 means connected with the runner frame adapted to open the valve of each tank during the passage of the receptacle under it, and a valve on each runner frame adapted to receive polishing medium from the receptacle thereon and to distribute the medium to each of the runner spindles on the frame in succession.
- 25

In witness whereof I have affixed my signature hereto.
